VERTICAL ROLLING MILL

Joseph M. O'Malley, Worcester, Mass., assignor
to Morgan Construction Company, Worcester,
Mass., a corporation of Massachusetts

Application March 27, 1946, Serial No. 657,486

8 Claims. (Cl. 80—31.1)

1

This invention relates to vertical rolling mills, and more particularly to mills of the type having multiple-grooved rolls and provision for moving the rolls vertically in order to bring selected grooves into position for operation upon the stock as it travels longitudinally along a horizontal path.

It is one object of the invention to provide a comparatively simple and dependable vertical rolling mill constructed to permit an extensive vertical adjustment of the rolls while maintaining an efficient driving connection between the rolls and a source of power.

It is a further object of the invention to provide a vertical rolling mill so constructed and arranged that the rolls may be adjusted through a wide range not only vertically to utilize various sets of roll grooves but also horizontally to operate upon bars of various widths, all without interfering with the driving of the rolls.

It is a further object of the invention to provide a vertical rolling mill so constructed and arranged as to facilitate the removal and replacement of the rolls.

With these and other objects in view, as will be apparent to those skilled in the art, the invention resides in the combination of parts set forth in the specification and covered by the claims appended hereto.

Referring to the drawings illustrating one embodiment of the invention and in which like reference numerals include like parts,

Fig. 1 is a vertical section through a vertical rolling mill, the section being taken on the line 1—1 of Fig. 5;

Fig. 2 is an enlarged detail view in section showing a portion of the roll-driving mechanism;

Fig. 3 is a section taken on the line 3—3 of Fig. 2;

Fig. 4 is a section taken on the line 4—4 of Fig. 2;

Fig. 5 is a side elevation of the mill, taken in the direction of the arrow 5 in Fig. 1;

Fig. 6 is a section taken on the line 6—6 of Fig. 5; and

Fig. 7 is a section taken on the line 7—7 of Fig. 5.

The embodiment illustrated comprises a fixed main housing 10 of the open top type, including four upright posts 11 arranged in two pairs at opposite sides of the mill pass line. The tops of the posts 11 in each pair are connected by horizontal housing caps 12 which are releasably secured to the posts by wedges 14. Each pair of posts 11 defines a main housing window 15.

2

A roll housing or cage 16 is slidable vertically within the windows 15. This housing comprises two vertically spaced hollow frames 18, each of generally rectangular shape to provide a window 19, these frames being integrally connected by four vertical posts 20. On one end of each frame 18 there are provided two laterally projecting flanges 22 (Fig. 6) which engage the outer surfaces of the two adjacent main housing posts 11, while the outer surfaces of the other two main housing posts are engaged by a horizontal clamping bar 23 secured to the adjacent roll housing posts 20 by bolts 24. Within each of the roll housing windows 19 there are slidably mounted two bearings 26 for the roll necks 27 of two grooved vertical rolls 28. These bearings are arranged to be adjusted by any suitable and well-known means including horizontal screws 30 mounted in the end portions of the frames 18. The bearings 26 are constructed to receive radial loads only, and the weight of the rolls is carried by suitable thrust bearings 31 at the upper ends of the rolls.

At some distance below the rolls there is provided a driving mechanism comprising a gear housing 33 which encloses a pair of intermeshing vertical pinions 34. One of these pinions has a downwardly extending shaft 35 on which there is mounted a bevel gear 37, this gear being driven by a bevel pinion 38 carried by a horizontal shaft 39. Each pinion 34 is provided with an upwardly extending shaft or neck 41 surrounded by a sleeve 42, each shaft 41 having a transverse notch 43 in its upper end shaped to provide two opposed concave seats for a pair of thin slippers 45 having outer convex cylindrical surfaces to engage the seats. The inner surfaces of the slippers are plane, and between them is located a transverse hammer head 46 on the lower end of an upright coupling spindle 47. A similar transverse hammer head 48 is provided on the upper end of each spindle.

The spindles 47 are operatively connected to the respective rolls 28 in such a manner as to permit vertical adjustment of the roll housing 16 and the rolls. For this purpose a coupling bearing carrier 50 in the form of a hollow horizontal rectangular frame is mounted beneath the roll housing 16 and arranged for vertical sliding movement in the windows 15 of the main housing 10. T-slots 51 are provided in the opposite ends of the carrier 50 to receive square heads 52 on the upper ends of two vertical screws 54. These screws extend through threaded holes in worm gears 55 which are rotatably supported in casings 56 and arranged to be driven by worms (not

shown) carried by a horizontal rotatable shaft 58. This shaft is driven by a reversible electric motor 59 through a chain-and-sprocket connection 60. The carrier 50 is provided with an elongated window 62 forming a guideway within which two coupling bearings 63 are mounted for horizontal sliding movement in the direction of roll adjustment, these bearings being located directly beneath the respective lower roll neck bearings 26. The coupling bearings 63 have laterally extending flanges 64 at their upper ends which overlap the sides of the carrier window 62. These flanges serve to support feet 65 which depend from the lower frame 18 of the roll housing 16. Thus the weight of the roll housing and rolls will rest upon the flanges and hold the coupling bearings 63 firmly in place to prevent vibration. Within each coupling bearing there is mounted a coupling element 67 which rotates about a vertical axis and serves to transmit driving torque to the roll thereabove.

The construction of the coupling element 67 is best shown in Figs. 2 to 4. Each coupling element comprises an outer cylindrical sleeve 68 and an inner member 69 fitting closely within the sleeve, these parts being fastened together by welding or other suitable means. An outwardly extending flange 70 is provided on the upper end of the sleeve to engage the coupling bearing 63 and thus support the weight of the coupling element. In the upper end of the inner member 69 there is provided a cylindrical counterbore 72 and a socket 73. The counterbore 72 is shaped to receive, preferably with a close fit, a cylindrical extension 74 on the roll neck 21, while the socket 73 is shaped to receive the usual wobbler 75 on the lower end of the roll neck. The wobbler should fit the socket with a slight clearance, so that the extension 74 will be free to align the coupling element correctly with the roll. Within the lower portion of the coupling element there is provided a vertically elongated guideway formed by providing a transverse slot 76 in the member 69, the slot having two opposed parallel vertical surfaces 77 which may be readily machined before the member 69 is assembled within the sleeve 68.

Within the slot 76 there is mounted a vertically slidable member 79 comprising two spaced vertical plates 80 having plane outer surfaces in contact with the surfaces 77 of the slot. These plates are integrally connected at their upper ends by a horizontal plate 81. On the inner sides of the plates there are provided two opposed concave seats for a pair of thin slippers 83 having outer convex cylindrical surfaces to engage the seats. The inner surfaces of these slippers are plane, and between them there is located the hammer head 48 of the adjacent spindle 47. The slippers 83 are connected to the hammer head by a transverse pivot pin 84. With this construction the spindle 47 has a driving connection with the coupling element 67 which is not only vertically telescopic but also universal, since the spindle can swing in one vertical plane about the pin 84, the hammer head turning between the slippers, while movement in a vertical plane at right angles to the first plane will be permitted by angular sliding of the slippers within their seats.

The gear housing 33 is protected against the entrance of water and scale by a cover plate 86 having holes 87 therethrough for the spindles 47. Each hole 87 is surrounded by an upstanding flange 88. A cap 90 is mounted on each spindle directly above the corresponding hole 87, each

cap having a depending flange 91 which surrounds the adjacent flange 88. For purpose of assembly the caps 90 may be made in two parts separable in an axial plane and bolted together.

The carrier 50 is preferably secured to the roll housing 16 by releasable means. For this purpose a pair of spaced ears 93 extend upwardly from each end of the carrier to straddle ears 94 depending from the roll housing, the ears having holes to receive transverse pins 95. These pins fit the holes in the ears 94 very loosely, so that none of the weight of the roll housing can rest on the pins.

The operation of the invention will now be apparent from the above disclosure. The shaft 39 will be driven by a suitable source of power, thus driving the bevel gearing 37—38 and the pinions 34. Driving torque will be transmitted from the pinions 34 through the spindles 48 and coupling elements 67 to the wobblers 75 and thus to the rolls 28. Since the spindles are universally connected at their opposite ends to the pinions and to the coupling elements respectively by an arrangement of slippers and hammer heads, the rolls may be considerably out of line with the pinions without causing any trouble. The rotating coupling elements 67 are well supported by the bearings 63 which are held firmly against vibration by the weight of the roll housing 16 resting on the bearing flanges 64. The screws 30 can be employed to adjust the roll neck bearings 26 in the roll housing windows 19, thus moving the rolls horizontally to adjust the width of the roll pass. During this adjustment the roll neck extensions 74, by their engagement with the counterbores 72, will cause the rotatable coupling elements 67 and their bearings 63 to slide horizontally in the window 62 of the carrier 50 and remain aligned with the rolls. To bring a different set of roll grooves into the pass line, it is merely necessary to loosen the clamp 23 and start the motor 59 in the desired direction. This will turn the worm gears 55 and move the screws 54 vertically, raising or lowering the carrier 50 and the roll housing 16. During this movement the coupling elements 67 will slide up or down over the members 79. When the rolls have reached the desired position the clamp 23 will be tightened to secure the roll housing 16 to the main housing 10 and thus prevent vibration. If a careless operator should attempt to lower the carrier 50 without first loosening the clamp 23, the pins 95 will prevent the carrier from moving downwardly away from the roll housing.

When the rolls are to be changed, the main housing caps 12 will be removed and the pins 95 withdrawn. The roll housing 16 can then be lifted vertically upward out of the main housing 10 by means of a crane, and another roll housing with the desired set of rolls therein may be lowered into place. Thus only a brief shut-down of the mill will be required.

Having thus described my invention, what I claim as new and desire to secure by Letters Patent is:

1. A vertical rolling mill comprising a main housing, a roll housing removably mounted in the main housing, a pair of vertical rolls in the roll housing and each having upper and lower necks, upper and lower roll neck bearings mounted in the roll housing to support the said necks and adjustable horizontally to and from one another, a coupling bearing carrier, means mounting said bearing carrier on the main housing in a position beneath the roll housing, said carrier being cen-

trally apertured to provide a guideway which extends horizontally in the direction of roll neck bearing adjustment, a pair of coupling bearings mounted in the carrier beneath the respective rolls and slideable horizontally along the guideway, a coupling element mounted within each coupling bearing and supported thereby for rotation about a vertical axis, means detachably connecting the upper ends of the coupling elements to the lower ends of the rolls to drive the same, a pair of intermeshing vertical pinions located beneath the coupling elements, and a pair of upright spindles universally connected at their lower ends to the respective pinions and at their upper ends to the respective coupling elements.

2. A vertical rolling mill as set forth in claim 1, in which the main housing is of the open top type, the roll housing is removable upwardly therefrom independently of the coupling bearing carrier, each roll has a wabbler on its lower end, and each coupling element has a socket in its upper end to receive the corresponding wabbler to drive the same.

3. A vertical rolling mill as set forth in claim 2, in which each roll has a cylindrical roll neck extension immediately above its wabbler, and each coupling element has a cylindrical counterbore to receive the corresponding roll neck extension with a close sliding fit.

4. A vertical rolling mill as set forth in claim 1, in which both the roll housing and the coupling bearing carrier are slideable vertically in the main housing, and vertically telescopic universal connections are provided between the upper ends of the spindles and the respective coupling elements.

5. A vertical rolling mill as set forth in claim 4, in which the lower portion of each coupling element is shaped to provide two opposed parallel vertical surfaces forming a vertically elongated guideway, there being a transverse hammer head on the upper end of each spindle located within

the corresponding vertically elongated guideway, slippers located on opposite sides of each hammer head, the slippers having outer convex cylindrical surfaces, means pivotally connecting the slippers to the hammer head, and a vertical plate between each slipper and the adjacent vertical surface and in sliding engagement with said surface, each plate having a concave seat on its inner side to receive the adjacent slipper.

10 6. A vertical rolling mill as set forth in claim 5, in which each coupling element includes an outer cylindrical sleeve and an inner member fitting closely within the sleeve, the lower portion of the inner member having a transverse slot therein forming the specified opposed vertical surfaces.

15 7. A vertical rolling mill as set forth in claim 1, in which both the roll housing and the coupling bearing carrier are slideable vertically in the main housing, and the weight of the roll housing rests upon the coupling bearings, means being provided to raise and lower the carrier.

20 8. A vertical rolling mill as set forth in claim 7, in which the coupling bearings have laterally extending flanges which slidably engage the upper surface of the carrier.
